TELEPHONE HANDSET

Otto Weeber, Berlin-Charlottenburg, Germany,
assignor to Siemens & Halske Aktiengesellschaft, Wernerwerk, Siemensstadt, near Berlin, Germany

Application April 17, 1931, Serial No. 530,853
In Germany July 19, 1930

2 Claims. (Cl. 179—158)

The invention relates to a telephone handset with built-in circuit switching springs which, when the handset is suspended, are operated by the weight of the handset.

5 The object of the invention is to produce a particularly simple and suitable arrangement for the operation of the switching springs and, according to the invention, this is achieved by the operating member of the switching springs being 10 influenced by the fork of the suspension hook supporting the receiver casing when the handset is suspended.

Due to this arrangement the construction of the handset is particularly simplified and an advantageous suitable position for the switch member 15 of the switch is obtained.

According to the invention the operating member is located on the inside of the handset at the junction between the handle and the receiver casing. When so located the switch member is in a 20 particularly favorable position for its operation by the suspension hook and is protected against unintentional operation during the handling of the instrument as the hand cannot come into 25 touch therewith.

The invention will be more fully described below in conjunction with a drawing.

The illustrated embodiment in Fig. 1 shows the upper part of such a handset when suspended and 30 Fig. 2 a similar view of this part when removed from the hook.

The casing 2, arranged at the upper part of the handle 1, is a receptacle for the receiver (not shown) as well as the contact springs 3 for the 35 automatic switch member. In the lower wall of the telephone casing 2 at a point 4 where this joins the handle 1, the switch member 5, operating the contact springs 3 of the switch, is movably fitted. Its movements are limited in both directions by

stops or the like. In order to obtain a favorable position for the switch member 5 against unintentional operation the point 4, at which the handle 1 joins the telephone casing 3, a channel is formed which is purposely made inaccessible to 60 prevent the user from touching the switch member 5 when gripping the handset.

When the handset is suspended a switch member 5 rests with its projecting part on the fork shaped end of the hook 6 which is so wide that it 65 furnishes a good support for the handle. The switch member 5 is thereby pressed inwards and actuates the middle contact of the set of springs 3 of the component representing the switchhook. In order to make the forked end of the hook 6 70 easy for the replacement of the handset the channel 4 is wedge shaped at the supporting point for the switch member 5, whereby a reliable operation of the switch member is obtained.

When the handset is lifted up, the switch member 75 5 moves outwards (Fig. 2). Being so short that it does not project over the front edge of the casing 2, it cannot be reached by the user's hand and is thereby protected against unintentional operation. As will be seen, the described and 80 shown construction constitutes a particularly suitable and simple arrangement for handsets of this type.

What is claimed is:

1. In a telephone handset, circuit-switching 85 springs, a button for actuating said springs, said button being located in a channel formed jointly by the handset handle and the receiver casing.
2. In a telephone handset, switching springs, and a button for actuating said springs located 90 in a channel of the handset, which protects the button against inadvertent operation when the handset is in use.

OTTO WEEBER.
